UNITED STATES PATENT OFFICE

IRVING H. JONES, OF MASSILLON, OHIO

DESIGN FOR A CLOCK CASING

Application filed May 23, 1931. Serial No. 39,946. Term of patent 3½ years.

To all whom it may concern:

Be it known that I, IRVING H. JONES, a citizen of the United States, residing at Massillon, in the county of Stark and State of Ohio, have invented a new, original, and ornamental Design for a Clock Casing, of which the following is a specification, reference being had to the accompanying drawings, forming a part hereof.

Fig. 1 is a plan view of a clock casing showing my new design. The ornamentation shown in part on the outer rim of the base is

to be extended entirely around the base, as indicated;

Fig. 2 is a front elevation;

Fig. 3 is a side elevation; and

Fig. 4 is a fragmentary full-size cross-sectional view on line 4—4 of Fig. 1.

I claim:

The ornamental design for a clock casing, substantially as shown and described.

In testimony whereof I affix my signature.

IRVING H. JONES.
